RADIO TUNING INDICATOR

William J. Schnell, Berwyn, Ill., assignor to Electrical Research Laboratories Inc., Chicago, Ill., a corporation of Illinois

Application May 15, 1937, Serial No. 142,864

8 Claims. (Cl. 116—124.1)

This application relates to a tuning indicator for radio receivers and the like.

In present day receivers of the most expensive type, so-called automatic tuning aids operable by various devices, such as telephone dials, push buttons and the like, have been provided for the purpose of facilitating tuning of the receiver in accordance with the call letters of a number of the most usually selected broadcasting stations.

It is an object of applicant's invention to provide a tuning indicator for the small and inexpensive class of radio receivers, which tuning indicators shall be simple in construction, inexpensive in cost, and efficient in operation.

A further object of applicant's invention is to provide an inexpensive and efficient marking device indicating the position to which the tuning element of the receiver should be moved to tune the receiver to the station represented by call letters inscribed on the marking device.

It is another object of applicant's invention to provide a plurality of tabs adapted to be inscribed with the call letters of any selected combination of broadcasting stations and inexpensive but efficient means to detachably mount said tabs upon the dial of a radio receiver.

A further object of the invention is to provide simplified inexpensive means operable in synchronism with the tuning element of the receiver to give a selective indication of the station to which the receiver is tuned.

Another object of the invention is to provide, in a radio receiver, a plurality of marking devices and means selectively illuminating the marking device representing the station to which the receiver is tuned at any instant.

Numerous other objects and advantages will be apparent from a consideration of the following specification when taken in consideration with the drawings disclosing one form of a device constructed in accordance with the principles of the present invention and in which—

Fig. 1 represents a perspective view of a radio embodying applicant's invention;

Fig. 2 and Fig. 3 are exploded views in perspective showing the various parts of the mechanism;

Fig. 4 is a view of a marking tab used in applicant's invention;

Fig. 5 is a vertical section taken along the line 5—5 of Fig. 6, and

Fig. 6 is a vertical section taken along the line 6—6 of Fig. 1.

As shown in Fig. 1, a radio cabinet 1 is provid-

ed with a dial assembly 2 visible through an opening in the front face of the cabinet, which opening, in the usual manner, is bounded by a decorative escutcheon 3. The dial assembly 2 comprises a frame or supporting plate 4 bolted or otherwise secured to the front panel of the radio cabinet. The frame 4 is generally rectangular in configuration and is provided with a rectangular opening 5. At the bottom of the opening a pair of brackets 6, secured to the front face of the frame provide a shelf on which is supported a sheet 7 and a glass plate 8. The sheet 7 is generally rectangular in shape; is somewhat larger than the opening 5 and is provided with a preferably circular opening 9. The front surface of the sheet 7 is blackened to prevent the reflection of rays toward the glass plate 8. This plate 8 is of a size substantially equal to the sheet 7 and on its front face are etched one or more semi-circular scales 10 marked with indicia representative of one or more broadcast bands. The back sheet 7 and the glass plate 8 are secured to the frame 4 and held against outward movement by a plurality of clamps 11. The clamps 11 are secured to the rear of the frame 4, passing through recesses 12 in the frame, and have portions 13 overlying the corners of the glass plate 8.

A lamp 14 is mounted by a bracket 15 on the upper edge of the frame 4 and a shield 16, surrounding the lamp 14, is provided with a longitudinal slot 17 in alignment with the glass plate 8. The lamp 14 serves as a means for diffusely illuminating the scales 10 by edge-lighting the glass plate 8.

A tuning condenser 18 of any ordinary form is mounted in the usual manner on the radio receiver chassis 19 and on the shaft 20 of the tuning condenser there is mounted, by a collar 21, a set screw 22 and a washer 23, a disc 24. The disc 24 is made of any suitable transparent or translucent material such as "Pyroxylin" and is coated on its rear surface with an opaque material, preferably black, in such a manner as to leave radially aligned transparent strips or lines 25 in the coating. The disc 24 is operated by a pair of fiber discs 26 carried on the inner end of a shaft 27 which is operable by a knob 28. A lamp 29 is mounted by a bracket 30 on the collar 21 in alignment with the transparent strips 25.

It will be apparent that for the coated disc 24 there may be substituted a like disc of opaque material having radially aligned slots allowing passage of the light therethrough.

A metallic plate 31 is secured to the frame 4

55

in tight engagement with the glass plate 8 by suitable bolts 32 and spacers 33. Plate 31 extends downwardly of the glass plate slightly more than half way and is provided with a semi-circular opening concentric to the upper scale 10 and inwardly of the edge of the glass plate 8. The plate 31 is cut or notched radially at equal spaced points to provide resilient sections 34 under which a marking tab 35 is adapted to be inserted and frictionally held against the glass plate 8. The resilient sections 34 are bent forwardly at their outer ends, as at 36, to facilitate the insertion of the tabs 35. The tabs 35 comprise transparent strips upon which there is or is adapted to be inscribed the call letters of desired broadcasting stations.

The frame 4 and associated parts are mounted on the chassis 19 by a bracket 37 fastened to the rear surface of the frame 4 and secured 20 to the condenser housing as by bolts 38. The bracket 37 is provided with a substantially semi-circular opening 39 forming a bearing for the shaft 20 of the condenser.

In use, tabs 35 are prepared by inscribing the 25 same with the call letters of the most frequently selected broadcasting stations; the receiver is tuned in turn to these stations and the tabs are in turn inserted under the lips 36, being pressed between the resilient sections 34 of the plate 31 30 and the glass plate 8 in alignment with the illuminated transparent slits or strips 25.

It will be seen that applicant has provided a 35 radio receiver having a plurality of marking devices, and has provided means for selectively illuminating the marking device representing the station to which at any instant the receiver is tuned.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

45 1. In apparatus of the character described, the combination of dial means comprising a light-transmitting plate and a scale visible through said plate, a second plate in clamping engagement with said first plate and having an opening 50 through which said scale may be viewed, and a plurality of marking tabs adapted to be inscribed with indicia representative of selected broadcasting stations, said second plate having a plurality of resilient sections for frictionally clamping said 55 tabs between said first and second plates.

2. In apparatus of the character described, the combination of dial means comprising a light transmitting plate and a scale visible through said plate, a second plate in clamping engagement with said first plate and having a semi-circular opening concentric to said scale, a plurality of marking tabs each adapted to be inscribed with indicia representative of a selected broadcasting station, said second plate being radially slit at equally spaced points to form a plurality of resilient sections for frictionally clamping said tabs between said first and second plates.

3. In apparatus of the character described, the combination of a translucent plate, an arcuate scale marked on one surface of said plate, means for directing rays of light against said plate diffusely to illuminate said scale, a second plate in clamping engagement with said first plate and having an opening concentric to said scale, 70 and a plurality of marking tabs each adapted to

be inscribed with indicia representative of a selected broadcasting station, said second plate having a plurality of resilient sections for frictionally clamping said tabs between said first and second plates, a tuning element, means for directing a concentrated beam of light upon said plates selectively to illuminate various lines of said scale and said tabs, and means for operating said directing means in synchronism with said tuning element.

4. In apparatus of the character described, the combination of a light transmitting plate, an arcuate scale visible through said plate, means for directing rays of light against said plate diffusely to illuminate said scale, a second plate and scale 15 in clamping engagement with said first plate and having an opening concentric to said scale, and a plurality of marking tabs adapted to be inscribed with indicia representative of a selected broadcasting station, said second plate having a 20 plurality of resilient sections for frictionally clamping said tabs between said first and second plates, a tuning element, a driving shaft for operating said element, luminous means carried by said shaft, a shutter carried by said shaft and interposed between said plate and said luminous means for directing a concentrated beam of light from said luminous means upon said plate selectively to illuminate various ones of said tabs in accordance with the position of said tuning element.

5. In apparatus of the character described, the combination of a translucent plate, an arcuate scale marked on one surface of said plate, means for directing rays of light against said plate diffusely to illuminate said scale, a second plate in clamping engagement with said first plate and having an opening concentric to said scale, and a plurality of marking tabs adapted to be inscribed with indicia representative of a selected broadcasting station, said second plate having a plurality of resilient sections for frictionally clamping said tabs between said first and second plates, a tuning element, a driving shaft for operating said element, luminous means carried by said shaft, a transparent disc having an opaque coating with an opening in said coating forming a transparent strip in alignment with said luminous means, said disc being carried by said shaft and interposed between said plate and said luminous means for directing a concentrated beam of light from said luminous means upon said plate selectively to illuminate various lines of said scale and various ones of said tabs in accordance with the position of said tuning element.

6. In apparatus of the character described, the combination of a translucent plate, an arcuate scale marked on one surface of said plate, means for directing rays of light against the edge of said plate diffusely to illuminate said scale, a second plate in clamping engagement with said first plate and having an opening concentric to said scale, and a plurality of marking tabs adapted to be inscribed with indicia representative of a selected broadcasting station, said second plate having a plurality of resilient sections for frictionally clamping said tabs between said first and second plates, a tuning element, a driving shaft for operating said element, luminous means carried by said shaft, a disc having a narrow radial slot in alignment with said luminous means, said disc being carried by said shaft and interposed between said plate and said luminous means for directing a concentrated beam of light from said luminous means upon said plate selectively to

illuminate various lines of said scale and various ones of said tabs in accordance with the position of said tuning element.

7. Means for detachably securing a plurality of marking tabs to the dial cover plate of a radio receiver, comprising a plate adapted to be placed in clamping engagement with the cover plate, said plate having a plurality of resilient sections for frictionally clamping said tabs between said plate and the dial cover plate.

8. Means for detachably securing a plurality of marking tabs to the dial cover plate of a radio receiver, comprising a plate adapted to be placed in clamping engagement with the cover plate, said plate being radially slit at equally spaced points to form a plurality of resilient sections for frictionally clamping the marking tabs between said plate and the dial cover plate.
